UNITED STATES PATENT OFFICE

DONALD E. RUTISHAUSER, OF ST. LOUIS, MISSOURI, ASSIGNOR TO HUSSMANN-LIGONIER COMPANY, OF ST. LOUIS, MISSOURI, A CORPORATION OF DELAWARE

DESIGN FOR A REFRIGERATOR DISPLAY CASE

Application filed September 8, 1930. Serial No. 36,901. Term of patent 7 years.

To all whom it may concern:

Be it known that I, DONALD E. RUTISHAUSER, a citizen of the United States of America, residing in the city of St. Louis, in the State of Missouri, have invented a new, original, and ornamental Design for a Refrigerator Display Case, of which the following is a specification, reference being had to the accompanying drawing forming a part thereof.

Fig. 1 of the drawing is a perspective view of a refrigerator display case, showing the front and one end of my new design.

Fig. 2 is a perspective view of a refrigerator display case, showing the front and the end opposite to the end of my new design shown in Fig. 1.

I claim:

The ornamental design for a refrigerator display case, as shown.

DONALD E. RUTISHAUSER.
